US00D475418S

(12) **United States Design Patent** (10) Patent No.: **US D475,418 S**
Manville (45) Date of Patent: ** Jun. 3, 2003

- (54) **CRAFT KIT CONSTRUCTION COMPONENT—AMORPHOUS, ASYMMETRIC FIN FORM WITH A SURFACE DECORATION**
- (75) Inventor: **Richard B. Manville**, Los Angeles, CA (US)
- (73) Assignee: **Mattel, Inc.**, El Segundo, CA (US)
- (**) Term: **14 Years**
- (21) Appl. No.: **29/157,964**
- (22) Filed: **Mar. 26, 2002**
- (51) LOC (7) Cl. **21-01**
- (52) U.S. Cl. **D21/484; D21/386**
- (58) Field of Search D20/22, 23, 27, D20/28; D21/386, 387, 390, 478–480, 484, 489–492, 504, 505; 446/85, 87, 102, 113; D1/112; D17/20; 84/322

Primary Examiner—Sandra L. Morris

(74) Attorney, Agent, or Firm—Kolisch Hartwell, P.C.

(57) **CLAIM**

The ornamental design for a craft kit construction component—amorphous, asymmetric fin form with surface decoration, as shown and described.

DESCRIPTION

FIG. 1 is a perspective view of the invention; and, FIG. 2 is a plan view of the invention.

1 Claim, 1 Drawing Sheet
